UNITED STATES PATENT OFFICE.

FREDERICK J. OSIUS, OF RACINE, WISCONSIN.

DRIVING MECHANISM FOR TREADLE-OPERATED MACHINES.

1,226,804.

Specification of Letters Patent. Patented May 22, 1917.

Application filed January 8, 1915. Serial No. 1,078.

To all whom it may concern:

Be it known that I, FREDERICK J. OSIUS, a citizen of the United States, and resident of Racine, county of Racine, and State of Wisconsin, have invented new and useful improvements in Driving Mechanism for Treadle-Operated Machines, of which the following is a description, reference being had to the accompanying drawings, which

10 are a part of this specification.

The invention relates to a driving mechanism comprising an electric motor which is adapted to be attached to a treadle operated machine, such as an ordinary sewing ma-

15 chine.

The invention further designs to provide a driving mechanism for a treadle operated machine in which the motor is secured to the machine itself and in driving connection with the hand wheel thereof and whose

20 operation is controlled by means connected to the treadle of the machine.

The invention further designs to provide means for holding the driving wheel of the

25 motor in yielding engagement with the driven wheel of the machine.

The invention further designs to provide means for controlling the operation of the motor which consists of a rheostat or a

30 brush control either one of which is adapted to be operated by means connected to it and to the treadle of the machine.

The invention further designs to provide a new and improved form of driving mech-

35 anism for a treadle operated machine.

The invention consists in the several features hereinafter set forth and more particularly defined by claims at the conclusion hereof.

40 In the drawings, Figure 1 is an end elevation of a sewing machine of usual construction with the driving mechanism thereon (parts of the sewing machine being shown in section); Fig. 2 is a plan view of the de-

45 vice embodying the invention; Fig. 3 is a side elevation thereof; Fig. 4 is a section taken on the line 4-4 of Fig. 3; Fig. 5 is a section taken on the line 5-5 of Fig. 1; Fig. 6 is a section taken on the line 6-6

50 of Fig. 5; Fig. 7 is a section taken on the line 7-7 of Fig. 1; Fig. 8 is an end elevation of the attachment showing the brush control (parts of the sewing machine being shown in section); Fig. 9 is a plan view of

55 this modified construction; Fig. 10 is a section taken on the line 10-10 of Fig. 8;

Fig. 11 is a section taken on the line 11-11 of Fig. 9; and Fig. 12 is a detail sectional view of the driving wheel of the motor.

The invention comprises an electric motor 60 12 of ordinary construction having an armature shaft 13 upon which a grooved friction pulley 14 having a peripheral portion 14' preferably of cork is mounted which is adapted to register with the hand wheel 15 65 of the machine 16, means for maintaining the driving wheel of the motor in yielding engagement with the driven wheel of the machine, means for controlling the operation of the motor and means connected to the controlling means and to the treadle of the machine for operating said controlling means.

The means for supporting the motor 12 upon the frame of the machine comprises 75 a bracket 17 pivotally connected to the frame of the machine and having a pin projection 18 thereon. The lower end of the

casing for the motor 12 is formed with a sleeve 19 which is adapted to surround the projection 18 on the bracket and rest upon the shouldered portion 20 thereof. A coiled

80 spring 21 surrounds the sleeve 19 and is anchored at its end 22 to the sleeve. The other end of the spring has an extension 23

extending outwardly from the sleeve and provided with a handle 24. The bracket 17

85 is provided with a series of upstanding projecting teeth 25 which the extension 23 is adapted to engage to thereby vary the tension of the spring 21 and thus form an adjustable yielding connection between the

motor 12 and the hand wheel 15. In Fig. 90 10 my preferred form of bracket is shown comprising a block 26, a pin 26' similar to

the pin 18, a band 27 adapted to extend around the upright member of the machine frame and having one end 28 looped over and secured in an aperture 29 in the block

26, the other end being provided with a screw 30 which is adapted to be inserted in an aperture in the block 26 and be secured thereto by a wing nut 31 whereby the turning

100 up of the wing nut on the bolt 30 will vary the length of the band 27 and rigidly secure it to the upright member of the

frame 16 of the machine. The block 26 has projections 25' similar to the projections 25

105 which are adapted to be engaged by the extension 23.

110 It will thus be noted that either one of the brackets will suitably support the mo-

tor in position upon the machine frame, that the spring 21 being connected at one end to the motor and that the other end adjustably connected with the bracket will form a yielding connection between the drive wheel of the motor and the driven wheel of the machine.

The means in the first instance for controlling the operation of the motor comprises a rheostat 32 having a swinging contact member 33 pivotally connected thereto at its end 34 and provided with spring retaining means 35. The contact arm is adapted to travel over contact plates 36 to cut in or out the resistances in circuit with the line connected to the motor.

The means in the second instance comprises rotary brushes 37 which are mounted upon a disk 38 surrounding the armature 39 which disk is yieldingly connected to the casing of the motor 12 by a coiled spring 40. The ends 41 of each of the brushes are adapted to register with the contact plates 42 on the armature and by advancing the brushes from vertical to horizontal position the flux through the armature is increased and the speed thereby is increased in the usual manner.

The means for operating either the rheostat or brush control comprises a rod 43 connected at one end to an eyed member 44 on the rheostat arm 33 or an eyed member 45 on the brush 37, the other end of said member being connected to one end of a spring 46, the other end of the spring 46 being connected to one end of a rod 47, the other end of said rod being connected to a hook-shaped bracket 48 through the aperture 49 therein, the hook portion of the bracket engaging one of the usual treadle members 50 of the machine and being locked in position by a set screw 51 in threaded engagement with the bracket and engaging the treadle member. Only limited movement of the treadle 45 and a limited rocking movement of the flywheel of the machine is permitted by a chain 52 connected to the frame of the machine and to a spring 53 which in turn is connected with the bracket 48.

50 The operation of the device is as follows: The current is turned on through the line including the motor in the ordinary manner and in the case of the rheostat the operator presses down upon the treadle in the usual manner as if operating the machine whereupon the rod 47, spring 46 and rod 43 will be moved downwardly carrying the contact arm 33 therewith to gradually cut out or insert the resistances in the circuit to 55 speed up or decrease the speed of the motor. When the brush is employed the downward movement of the rod 47, spring 46 and rod 43 will cause the brushes to assume a horizontal position to speed up the motor and it is obvious that in either case the con-

60 trol may be so positioned by the operation of the treadle as to increase or decrease the speed of the motor and thereby increase or decrease the speed of the sewing machine to which it is attached or to stop the operation of the motor and consequently that of the machine.

65 The invention thus exemplifies a mechanism for driving a treadle-operated machine comprising a motor mounted upon the frame of the machine and in operative relation with the driven wheel of the machine, means for controlling the speed of the motor and operating means connected to said controlling means and to the treadle of the machine whereby the operator may control the motor through the operation of the treadle mechanism.

70 The invention is not to be restricted to the details of construction herein set forth but may be varied so as to be within the scope 75 of the appended claims.

75 What I claim as my invention is:—

1. The combination, with a machine having a wheel to be driven, of an electric motor including a frame and a driving wheel, a support secured to the frame of the machine and having an upstanding projection thereon, a sleeve on the motor-frame surrounding said projection to swingingly mount said motor on said support to bring said drive wheel into driving engagement with said driven wheel, and a spring connected to said sleeve and to said support to yieldingly maintain said wheels in driving relation.

80 2. The combination, with a machine having a wheel to be driven, of a support secured to the frame of the machine, an electric motor provided with a drive wheel and mounted on said support to move in a substantially horizontal plane to bring said drive wheel into frictional driving engagement with said driven wheel, and a spring secured to said motor and adjustably secured to said support for yieldingly maintaining said wheels in driving relation.

85 3. The combination, with a machine having a wheel to be driven, of a support secured to the frame of the machine, an electric motor provided with a drive wheel and swingingly mounted on said support to bring said drive wheel into frictional engagement with said driven wheel, a spring for yieldingly maintaining said wheels in driving relation, and means on said support for securing said spring in different positions of adjustment.

90 4. The combination, with a machine having a wheel to be driven, of a support secured to the machine, an electric motor provided with a drive wheel and revolubly mounted on said support to bring said drive wheel into frictional engagement with said driven wheel, and a spring secured at one

end to the motor for yieldingly maintaining said wheels in driving relation, said support having a plurality of locking recesses therein, the other end of said spring being adapted to be held in any of said locking recesses. 5

5. The combination, with a machine having a wheel to be driven, of a support, means comprising a band for removably clamping 10 said support to the machine, an electric motor swingingly mounted on said support and provided with a drive wheel for frictional engagement with said driven wheel, and means for yieldingly maintaining said 15 wheels in driving relation.

6. The combination, with a machine having a wheel to be driven, of a support detachably secured to the frame of the machine, an electric motor provided with a 20 drive wheel and mounted on said support to move in a substantially horizontal plane to bring the periphery of said drive wheel

into driving engagement with the periphery of said driven wheel, and means for automatically yieldingly maintaining said 25 wheels in driving relation.

7. The combination, with a machine having a wheel to be driven, of a support detachably secured to the frame of the machine and having an upstanding projection 30 thereon, a motor horizontally swingingly mounted upon said support and projection so as to bring the periphery of its drive wheel into engagement with the periphery of said driven wheel, and means for 35 automatically yieldingly maintaining said wheels in driving relation.

In testimony whereof, I affix my signature, in presence of two witnesses.

FREDERICK J. OSIUS.
